(57) **CLAIM**

The ornamental design for a structure for a child play area as shown and described.

DESCRIPTION

FIG. 1 is a perspective view of a structure for a child play area in an open configuration showing our new design; FIG. 2 is another perspective view thereof in a closed configuration;

FIG. 3 is another perspective view thereof;

FIG. 4 is a front view thereof;

FIG. 5 is a rear view thereof;

FIG. 6 is a right side view thereof;

FIG. 7 is a left side view thereof;

FIG. 8 is a bottom view thereof; and,

FIG. 9 is a top view thereof.

The broken lines in the figures form no part of the claimed design.
